UNITED STATES PATENT OFFICE

CHARLES W. LEGUILLOON, OF AKRON, OHIO, ASSIGNOR TO THE B. F. GOODRICH COMPANY, OF NEW YORK, N. Y., A CORPORATION OF NEW YORK

DESIGN FOR A RUNNING-BOARD MAT

Application filed June 9, 1931. Serial No. 40,144. Term of patent 14 years.

To all whom it may concern:

Be it known that I, CHARLES W. LEGUILLOON, a citizen of the United States, residing at Akron, in the county of Summit and State of Ohio, have invented a new, original, and ornamental Design for a Running-Board Mat, of which the following is a specification, reference being had to the accompanying drawings, forming a part thereof.

Fig. 1 is a perspective view of a running-board mat showing my new design.

Fig. 2 is a fragmentary plan view on a larger scale of the running-board mat shown in Fig. 1.

Fig. 3 is a section on line 3—3 of Fig. 2.

I claim:

The ornamental design for a running-board mat substantially as shown.

CHARLES W. LEGUILLOON.
